UNITED STATES PATENT OFFICE.

SPENCER T. GULLICKSEN, OF CHICAGO, ILLINOIS, ASSIGNOR TO J. H. BUNNELL & COMPANY, OF NEW YORK, N. Y.

DESIGN FOR A TICKER STAND OR SIMILAR ARTICLE.

Application filed January 30, 1929. Serial No. 29,852. Term of patent 7 years.

To all whom it may concern:

Be it known that I, SPENCER T. GULLICKSEN, a citizen of the United States, residing at Chicago, county of Cook, and State of Illinois, have invented a new, original, and ornamental Design for a Ticker Stand or Similar Article, of which the following is a specification, reference being had to the accompanying drawing, forming part thereof.

The drawing illustrates a perspective view of the article showing my new design.

What I claim is:

The ornamental design for a ticker stand or similar article, substantially as shown.

SPENCER T. GULLICKSEN.
